UNITED STATES PATENT OFFICE.

WALDEMAR DYRSSEN, OF NEW YORK, N. Y.

FURNACE.

Application filed June 28, 1923. Serial No. 648,254.

To all whom it may concern:

Be it known that I, WALDEMAR DYRSSEN, a citizen of the United States, and resident of the city, county, and State of New York, have invented certain new and useful Improvements in Furnaces, of which the following is a specification.

This invention refers to open hearth and other furnaces having regenerators for pre-heating the combustion air and to the method and means for reversing the direction of flow of air through the regenerators, but with the flame flowing constantly in the same direction through the melting chamber. In an ordinary open hearth furnace the combustion air and sometimes the fuel, as for instance in the case of producer gas, is preheated in regenerators and at the reversal of the flow in the regenerator chambers the flame is also reversed in the melting chamber, so that at one period the flame enters the melting chamber at the left hand end of the furnace and the next period at the right hand end.

It has been proposed before, to use uni-directional flame, that is, to have the combustion air and fuel enter the melting chamber from one end only at all times. The flow of air through the regenerators as heretofore arranged was reversed by manipulating valves in the passages between the regenerators and the ends of the furnace. Such valves are necessarily located where the waste gases from the furnace and the combustion air are hottest. These valves do not stand up in practice except with the use of extreme water-cooling which, however, cools down the gases and the combustion air to such an extent that the proper flame temperature cannot be maintained in the furnace. On account of this disadvantage, the uni-directional flame furnace has not been successfully used and is not used at the present time.

In my invention I have no valves in the hot flues between the regenerators and the melting chamber; either in the waste gas passage or in the hot air passage. Instead of valves, I provide means for creating the necessary pressure difference by the use of nozzles, according to the induced draft method. These nozzles can either function in such a way that the flow of gases is obtained or they can function in such a way that the openings in the gas passages are filled with the gas introduced through the

nozzle, creating a pressure difference in the flues at this point, so that no gases pass through the flue. In other words, the induced draft acts as a shut off valve. 60

I have illustrated embodiments of the invention in the accompanying drawings in which Fig. 1 is a plan view of the furnace and associated parts;

Fig. 2 is a vertical section on line 2—2 of Fig. 1 through the melting chamber and ends of the furnace;

Fig. 3 is a vertical section on line 3—3 of Fig. 1 through one of the regenerators of the same furnace; 70

Fig. 4 is a plan of a somewhat modified furnace;

Fig. 5 is a section on line 5—5 of Fig. 4.

Referring to Fig. 1 the furnace illustrated has the usual hearth 1, a front wall 2 with door openings 2' and a back wall 3 with the tapping spout 4. The fuel and air are introduced at the right end 5 of the furnace, and products of combustion are withdrawn at the left end 6. In this furnace, only the air is preheated and therefore only two regenerators 7 and 8 are used. The upper parts 9 of the regenerators 7 and 8 communicate through Venturi shaped openings 10 and 11 respectively with a common flue 12, having a port opening 13 at the end 6 of the melting chamber. At points in the wall opposite the openings 10 and 11 are nozzles 14 and 15 through which waste gases are supplied under pressure through pipes 16 and 17 by a fan 18 which takes the gases directly from the stack 19. The upper part 9 of each of the regenerators also communicates through flues 20 and 21 respectively with Venturi-shaped openings 22 and 23 95 with the vertical flue 24 at the burner end of the furnace. The air inlet flue to the melting chamber is inclined as indicated by 25 (Fig. 2) at the point where the fuel is introduced through burner 26. The fuel used is either tar, coke oven gas, powdered coal, fuel oil, natural gas or producer gas. 100

At points in the walls opposite the Venturi openings 22 and 23, nozzles 27 and 28 are mounted. These nozzles are supplied with waste gases under pressure through pipes 29 and 30, from fan 18. The respective lower part 31 of the regenerator chamber communicates by flues 32 and 33 respectively with the stack 19. Shut-off valves 32^a and 33^a are placed in these flues, and fan 35 supplies combustion air alter-

nately through pipes 32^b and 33^a to flues 32 and 33, the direction of flow being controlled by means of a three-way valve 36. Valves 16^a, 17^a, 29^a and 30^a are provided in the 5 four pipes 16, 17, 29 and 30 as shown.

In operation for one period the stack valve 32^a in flue 32 is closed and air is supplied from fan 35 through the pipe 32^b and flue 32. The air enters at the bottom 10 of regenerator 7 and flows upward through the checker bricks which have been previously heated and the air is thus heated when it reaches the upper part of the regenerator. From here the air flows 15 through flue 20, to opening 22 and flue 24 where it meets the fuel introduced through the burner 26. The flame is introduced in the melting chamber above the hearth 1 and the waste gases are drawn through the 20 port opening 13 into flue 12. From this flue the gases flow through the opening 11, into the upper part of the regenerator 8 and the waste gases descend through the checker work, heating up same, and are 25 finally withdrawn through flue 33 leading to the stack 19, the stack valve 33^a being open at this time. There is, however, lower pressure in the waste gas flue 12, than in the upper part of regenerator 7. The air 30 in this part would therefore have a tendency to flow directly into flue 12 if there were no means of preventing it from doing so. In order to prevent this flow, the valve 16^a in pipe 16 is opened and waste gases introduced through the nozzles 14 at this 35 point. These waste gases create such a condition in the Venturi port 10 that a pressure difference will exist between the regenerator or right hand side and the waste gas flue side or left hand of this 40 opening. If the quantity and the pressure of the gases introduced at 14 is proper, there will be no flow of air or waste gases through opening 10, and the relatively small quantity of waste gases introduced through the 45 nozzle 14 will pass off through flue 12, into regenerator 8, with the waste gases coming from the melting chamber.

In a similar way there exists a pressure 50 difference between flues 24 and 21, and waste gases under pressure are introduced at 28, in order to prevent flow of air through opening 23, in the same manner as described in opening 10. There is no need 55 at this time of a flow of waste gases through the nozzles at 27 and 15. The waste gas jets that are used as a means of shutting off openings 10 and 23, cool down the waste gases to a certain extent before they enter 60 the checker-work in regenerator 8. However, the cooling down will not be sufficient to interfere with the proper heating of the checker-work in the regenerators which pre-heat the air to the desired temperature.

65 When the flow of air and waste gas

through the regenerators is reversed, the stack valve 32^a in flue 32 is opened and the valve 33^a in flue 33 closed and valve 36 is shifted to divert the air from the fan into flue 33. The valves 16^a and 30^a in 70 pipes 16 and 30 respectively are closed and the valves 17^a and 29^a are opened in pipes 17 and 29, thus reversing the flow of air and waste gas in the regenerators but not in the melting chamber thus it is clear 75 that the flame and gases flow constantly in the same direction through the melting chamber.

Referring to the modified arrangement shown in Figs. 4 and 5, the outlet 39 from the melting chamber is Venturi-shaped and of oblong form as indicated. There is an oblong nozzle 40 in the roof above the opening 39 through which waste gases under pressure are introduced. Opening 39 communicates with a flue 41 which communicates with the upper parts of regenerators 42 and 43. The other end of the upper part of each of the regenerators 42 and 43 communicates by a flue 44, with the burner 85 end of the furnace. The burner 50 indicated in Fig. 5 is suitable for producer gas coming directly from the producers. The producer gas comes through pipe 45, provided with a regulating valve 46, and is 90 introduced into the burner through flue 47. The lower parts of the regenerators communicate with the stack, not shown, by flues 48 and 49, in substantially the same way the flues 32 and 33 are connected as explained 100 with reference to Fig. 1; and the combustion air is supplied to either flue 48 or 49 in a similar way, as described with reference to that figure.

In operation of the arrangement shown 105 in Figs. 4 and 5, the stack valve in flue 48 is closed and combustion air is introduced into this flue. The air is preheated in regenerator 42, and flows to the burner through flue 44. The waste gases are withdrawn through the opening 39 and flue 41 to regenerator 43, and pass alternately to the stack through flue 49. There is, however, a pressure difference between the upper parts of regenerator 42 and flue 41 so 110 that the combustion air would tend to pass directly into flue 41 if this pressure difference was not eliminated. In the same way air would pass from the upper part of regenerator 42 through flue 44 to regenerator 115 43 and to the stack, if the pressure difference was not eliminated. The elimination of this pressure difference is accomplished by blowing a jet of waste gas at a fairly high pressure from the nozzle 40 into the Venturi port 39 and the pressure difference is created between the melting chamber and flue 41. If the pressure of the waste gases through nozzle 40 is properly regulated, the 120 pressure in flue 41 and in the upper part 125

of the checker chamber 42 will be exactly the same and there will be no flow of air or gas through the opening 42^b between 42 and 41. The opening 42^a between the 5 regenerator 42 and flue 44 and the regenerator 43 and flue 41 respectively are of such area that the loss of pressure of the air and gases passing through these openings is the same, hence there will be no pressure 10 difference between flue 44 and regenerator 43 and no air will pass this way to the regenerator 43. The desired flow of air and waste gas is therefore obtained by the use of a single nozzle which is pulling 15 the waste gases from the melting chamber at all times. The reversal of flow of the gases through the regenerators is accomplished by simply reversing the stack valves and the flow of combustion air from 20 the fan.

Instead of using the waste gases under pressure to create the necessary pressure differences in the system, hot air can also be used and various other instrumentalities 25 and combinations than those indicated in the drawings and described herein can be used to perform the functions set forth without departing from the invention as defined in the appended claims.

30 The gases used to create the necessary pressure differences can be introduced at other locations than those shown, and gases other than waste gas can be used. For example, either cold or hot air can be introduced in the flue 44 between the regenerators and the burners or fuel gas can be introduced under pressure through the burners themselves.

In the foregoing description, I have referred 40 to the furnace as an open hearth furnace, and have described the method with certain references to passing the flame or gases through the melting chamber. It is to be understood, however, that my invention is applicable to other furnaces in which no melting takes place, such as furnaces for heating blooms, billets and the like. The term open hearth furnace as used in the claims is intended to cover such other furnaces, and the term melting chamber is intended to cover also a heating chamber in which no melting necessarily takes place.

Though I have described with great particularity the steps of my improved method 55 and details of the apparatus for embodying the invention, it is not to be construed that I am limited thereby as changes may be made by those skilled in the art without departing from the invention as defined in the appended claims.

What I claim is:

1. The method of controlling communication 65 between the melting chamber of a metallurgical furnace and a regenerator through a port which is always open, which

consists in directing a jet of gas toward the open port to practically or substantially equalize the pressure on both sides thereof.

2. The method of operating an open hearth furnace which consists in supplying 70 the fuel and air to the melting chamber constantly in one direction, and alternately passing the combustion air and waste gases through separate regenerators and introducing jets of gas to control the direction of 75 the circulation of air and waste gases through the regenerators.

3. In combination with a furnace, a pair 80 of regenerators, means for supplying air thereto, a flue connecting the regenerators, normally open ports connecting said flue with each of said regenerators, normally open ports connecting each regenerator with the furnace and means for introducing a jet of gas toward certain of said ports to 85 alternately control the circulation of air through one of said regenerators to the furnace and the passage of waste gases from the furnace.

4. In combination with an open hearth 90 furnace, a pair of regenerators, passages which are always open connecting the furnace with said regenerators, and means for introducing jets of gas to control the circulation of combustion air and waste gas 95 through said passages, the regenerators and the furnace.

5. In combination with an open hearth furnace and regenerators communicating therewith, means for causing the flame to pass constantly through the melting chamber of the furnace in the same direction comprising means for alternately supplying air to each regenerator, flues connecting the regenerators with the furnace at one end, 100 ports at the opposite end of the furnace communicating with said regenerators and means for directing jets of gas so as to permit the flow of the air and waste gases through certain of said ports and flues and 105 prevent the flow through other ports and flues.

6. In combination with an open hearth furnace, a pair of air regenerators, a flue connecting said regenerators, a port leading 115 from said flue to the melting chamber of the furnace, ports connecting said flue with each of said regenerators, other ports connecting the regenerators with the fuel inlet end of the melting chamber, means for alternately supplying air to each of said regenerators and means for directing jets of waste gas toward certain of said ports so as to alternately permit the air to pass through one of said regenerators to the melting 120 chamber and the waste gas to pass from the melting chamber through the other regenerator.

7. In combination with an open hearth 125 furnace, a pair of regenerators and means 130

- for causing the flame to pass constantly through the melting chamber of the furnace in the same direction without the use of valves in the ports leading thereto, comprising flues for alternately supplying air and withdrawing waste gases from the regenerators, a flue connecting the regenerators, a port at the outflow end of the melting chamber connected with said flue, 10 Venturi shaped ports connecting each of the regenerators with said flue, Venturi shaped ports connecting the regenerators with the fuel inlet end of the melting chamber, nozzles opposite each of said Venturi shaped 15 ports, means for discharging a fluid through said nozzles and valves for cutting off the supply of fluid to certain of said nozzles.
8. In combination with an open hearth furnace, a pair of regenerators, a plurality of Venturi shaped ports through which the combustion air and waste gases pass respectively to and from the furnace, and means associated with each of said ports for directing a jet of fluid toward certain selected 25 ports so as to determine which ports the air and waste gas will traverse.
9. The method of controlling communication between a chamber in a furnace and a regenerator through a port which is always 30 open, which consists in directing a jet of gas toward the open port to prevent com-

munication between the chamber and the regenerator through said port.

10. In combination with a furnace and the regenerators thereof, means for utilizing 35 fluid jets at different locations to exert just sufficient pressure to control the circulation of the combustion air and waste gas through the regenerators and the furnace without the use of valves in the flues which said combustion air and waste gas traverse.

11. In combination with a uni-directional furnace and the regenerators communicating therewith, means causing the combustion gases to pass constantly through the melting 45 chamber of the furnace in the same direction comprising means for supplying air to either regenerator, flues connecting the regenerators with the furnace at one end, ports at the opposite end of the furnace communicating with passages leading to said regenerators, and means for creating a pressure difference between certain ports so as to cause the flow of air and waste gas through certain of said ports and flues and 55 prevent the flow through other ports and flues, without the use of valves located in the ports and flues which the gas and air traverse.

In witness whereof, I have hereunto 60 signed my name.

WALDEMAR DYRSSEN.
